CLAIM

The ornamental design for a spa control panel, as shown and described.

DESCRIPTION

FIG. 1 is a top, plan view of a spa control panel showing our design;

FIG. 2 is a front elevational view thereof;

FIG. 3 is a back elevational view thereof;

FIG. 4 is a bottom view thereof;

FIG. 5 is a left side elevational view thereof;

FIG. 6 is a right side elevational view thereof; and,

FIG. 7 is a front elevational view of an alternate embodiment of the spa control panel shown in FIGS. 1-6, the other views of this alternate embodiment being the same as shown in FIGS. 1, and 3-6.

FIG. 1

FIG. 2

FIG. 3
